UNITED STATES PATENT OFFICE.

JOHN T. BINKLEY, OF CHICAGO, ILLINOIS.

LOCKING DEVICE FOR TRAVELING-CASES, SAMPLE-CASES, &c.

1,022,817.

Specification of Letters Patent.

Patented Apr. 9, 1912.

Application filed December 7, 1911. Serial No. 664,414.

To all whom it may concern:

Be it known that I, JOHN T. BINKLEY, a citizen of the United States, residing at Chicago, in the county of Cook and State of Illinois, have invented a new and useful Improvement in Locking Devices for Traveling-Cases, Sample-Cases, &c., of which the following is a specification.

The object of the present invention is to provide a more secure locking device for use in connection with suit cases, or in analogous situations, such device being capable of ready manipulation.

In the embodiment shown, the invention comprises an interiorly mounted, preparatorily set, spring-retracted slide carried by one section of the case and equipped with a series of laterally projecting hook-form catches which, when the slide is in the "set" position are adapted to spring over and into engagement with the studs or catches which are interiorly carried by the other case-section, the slide being normally held in the "set" position by a spring-catch; and a key-controlled plunger or push-button which extends through the escutcheon-plate and is adapted, when unlocked, to be pushed in to release the last-mentioned catch, thereby permitting the slide to be retracted and thus to disengage the hook-form catches from the studs mentioned.

From the foregoing, it will be understood that my invention comprises an automatically engaging locking device which is adapted to be automatically shifted to the non-locking position when the push-button, after it is unlocked by the key, is pushed in to disengage the slide-latching catch from the stop with which it is normally in engagement.

The invention is illustrated in its preferred embodiment in the accompanying drawings, in which—

Figure 1 represents a horizontal sectional view of a suit-case equipped with my improved locking device, the section being taken as indicated at line 1 of Fig. 2, so that the view is toward the inner surface of the top of the case; Fig. 2, a broken vertical section taken as indicated at line 2 of Fig. 1, the suit-case being upright, in this position; Fig. 3, an enlarged broken vertical section taken as indicated at line 3 of Fig. 1, this view illustrating the manner in which the slide-retaining catch engages a stationary catch carried by the locking

plate when the slide is in the "set" position; Fig. 4, a broken vertical section taken as indicated at line 4 of Fig. 2; Fig. 5, an elevational view of the lock-casing removed from the suit-case and escutcheon; Fig. 6, an enlarged vertical section through the key-controlled, inwardly movable plunger or push-button and its barrel, the section being taken as indicated at line 6 of Fig. 5; Fig. 7, a horizontal section taken as indicated at line 7 of Fig. 6, this view showing a fragment of the tumbler which is shown in section in Fig. 6; Fig. 8, a view similar to Fig. 6, but showing a key inserted in the key-controlled plunger; and Fig. 9, a section taken as indicated at line 9 of Fig. 8, this view illustrating the manner in which the tumbler is retracted to permit the push-button to be rotated through the medium of the key.

In the illustration given, A, A' represent sections of a case, such as a suit-case, sample-case, medicine-case, or the like; B, an interiorly mounted, longitudinally-shiftable slide carried by the top-flange 1 of the casing-section A'; and C, key-controlled mechanism through the medium of which the slide B may be freed from its set position and permitted to move under the force of its spring to the non-locking position.

It is usual to connect the lower flanges or bottom members of the sections of a suit-case of this character by hinges, such as the hinges 2 shown in Fig. 4; also, to provide the top-flange 3 of the section A with a handle 4. At the free edges of the top, end, and bottom flanges of the casing-section A is provided the usual reinforcing rim member 5, which may be of metal; and the upper part of the member 5 is equipped with downwardly or inwardly projecting studs, or stationary catches, 6, shown as four in number.

The section A', which may be termed the lid section of the suit-case, is provided with the usual reinforcing bar 7 for the top, bottom and end flanges; and upon the top member of the bar 7 is mounted the freely movable slide B. For this purpose, the top member of the bar 7 is equipped with a series of headed guide-studs or screws 8 which depend from said member and engage slots 9 in the slide B. The studs 8 are equipped with washers or spacing members 10, affording bearings for the upper side of the slide. The edge of the slide B which is toward the

section A is equipped with a series of laterally-projecting hook-form catches 11 which are adapted to engage the studs 6. The slide B and the members 11 are of resilient material, and the members 11 incline downwardly somewhat, that is, toward the bottom of the suit-case, so that, assuming the slide B to be in the set position, the inclined upper surfaces of the members 11 will ride over the ends of the studs 6 when the suit-case is closed, and the members 11 will spring into locking engagement with the studs 6, that is, the slots or grooves 12 of the hooks will receive the studs 6 after the members 11 have been sprung laterally in the action of closing the suit-case sections. The slide B is adapted to be retracted from its locking position by a spring 13, shown in the form of a wire loop or yoke, whose web is pivotally connected at 14 with one end of the slide and whose arms are secured to the end-flange 15 of the casing-section A', as by means of a clamp 16. The slide is equipped with a downwardly projecting operating lug, or handle, 17 which may be formed integrally with the slide by partially severing a portion of the metal and striking it downwardly, and the slide is also equipped with an upwardly struck locking tongue, or spring catch, 18 which normally engages a fixedly carried catch 19, assuming the slide B to be in the "set" position. The slide B is moved to the "set" position through the medium of the actuating member 17 against the force of the spring 13, preparatory to closing the suit-case.

The key-controlled mechanism C through the medium of which the slide-holding catch 18 may be depressed to permit the slide B to move automatically to the non-locking position, comprises a barrel 20 in which is mounted a revoluble key-controlled plunger, or push-button, 21, a tumbler 22 serving as a releasable device for holding the plunger 21 in its elevated position and preventing rotation of the plunger, except through the medium of the key. The barrel 20 is fixedly mounted on a frame 23 which comprises a bottom-plate 24 and a U-shaped plate 25 which is securely mounted thereon. The bottom-plate 24 of the frame 23 carries the stop, or fixed catch-member, 19; and the ends of the plate 24 project beyond the member 25 and are secured, as by screws 26, to the bar 7 of the casing-section A'. The push-button 21 has a reduced upper end which projects above the barrel, or cylinder, 20, and in the member 21 is a longitudinal key-receiving slot 27. The barrel 20 extends through a perforation in the member 25, and the plunger 21 has a reduced lower end which extends through a perforation 28 in the plate 24. Thus, the lower end of the plunger is cut away or reduced to afford a circumferential groove 29, as seen in Fig. 6. The tum-

bler 22 is mounted in the frame 23 on a vertically disposed pivot 31 and has its opposite end provided with a laterally turned short tooth 32 and a similarly turned longer tooth 33, the barrel 20 being cut away, as indicated at 32^a and 33^a to accommodate said teeth. The tooth 32 is adapted to engage the key-groove 27 of the plunger; and the tooth 33 is adapted to engage the circumferential groove or cut away part 29 of the plunger, so that the tooth 32 will serve to prevent rotation of the plunger, while the tooth 33 will serve to prevent depression of the plunger. When, however, a key, such as the key 34 shown in Fig. 8, is inserted in the slot 27, it serves to retract the tumbler by engagement with the inturned extremity of the tooth 32, so that the plunger can be rotated to throw the slot 27 out of registration with the tooth 32. In the illustration given, the barrel 20 has its outer end spun inwardly and provided with a slot 35 to permit insertion of the key and a slot 36 at an angle of 180° thereto to permit withdrawal of the key. The plunger-locking pawl, or tumbler, 22 is equipped with a spring 37, one end of which is connected with the tumbler and the other end of which is connected with a pin 38 with which the frame 23 is fitted, so that the spring will move the tumbler to the locking position when the plunger 21 is elevated and in the proper angular position and the key removed. Any suitable means (not shown) may be employed to prevent the use of any other than the authorized key.

The upper end of the barrel 20 is housed in an escutcheon 39, and the reduced upper end of the plunger 21 projects through a perforation 40 in the escutcheon-plate.

The operation may be described briefly. Preparatory to closing the casing sections A, A', the casing-locking member B is shifted to the "set" position shown in Fig. 3, in which position the catch or locking member 18 of the member B engages the stationary catch or shoulder 19 of the plate 24. When the casing-sections are swung together with the locking-member B thus set, the stud-engaging members 11 ride over the stud 6 and spring into locking engagement therewith, the resiliency of the members 11 and the member B by which they are carried, permitting this operation. In this position of the parts, the spring-catch 18 maintains the plunger 21 in an elevated position; and when the plunger is turned to the proper angular position the tumbler 22 will drop into locking engagement therewith, the tooth 32 entering a longitudinal groove 27, and the tooth 23 entering the circumferential groove 29 so that the plunger will be locked both against rotation and depression. The unlocking operation is performed by inserting a key, thereby retracting the tumbler from the locking position, and when the

key is turned, the tooth 32 will ride on the smooth surface of the plunger, thereby holding the tumbler retracted. The key can be withdrawn after a half rotation; and the 5 plunger is thereupon free to be depressed to release the spring-catch 18 from engagement with the shoulder 19, whereupon the spring 18 will operate to retract the case-locking member B, withdrawing the hook-form 10 catches 11 from engagement with the studs 6.

It will be noted that the construction enables as many locking points to be employed as the length of the case may render desirable; also, that the locking occurs automatically 15 when the case sections are closed; and finally that the only force which need be exerted upon the key 34 is that necessary to retract the tumbler 22 and turn the plunger in its bearing, the case-locking member B 20 being automatically retracted when the plunger 21 is depressed, thus disengaging the spring-catch 18 from the shoulder 19.

The invention is adapted for use in connection with cases for various purposes, 25 satchels, etc., and the claims are to be construed accordingly.

The foregoing detailed description has been given for clearness of understanding only, and no undue limitation should be 30 understood therefrom.

What I regard as new, and desire to secure by Letters Patent, is—

1. The combination with a case having parts adapted to be closed together, of 35 catches carried by one of said parts, and a normally restrained locking-member carried by the other of said parts and equipped with a plurality of catches adapted to automatically engage said first-named catches, potential means for retracting said locking-member, and means for disengaging said locking-member to permit its retraction.

2. The combination with a case having parts adapted to be closed together, of a 45 series of catches carried by one of said parts, and co-acting mechanism comprising a preparatorily-set, potentially-movable locking-member equipped with a plurality of catches, and key-controlled means for releasing said locking-member to permit retraction thereof.

3. The combination with a case provided with parts adapted to close together, of a series of catches carried by one of said parts, 55 and co-acting mechanism comprising a preparatorily-set, potentially-movable locking-member equipped with a series of catches adapted to automatically engage said first-named catches, and a key-controlled member adapted to free said locking-member to permit retraction thereof.

4. The combination with a case having parts adapted to close together, of a series 65 of catches carried by one of said parts, and co-acting mechanism carried by the other of said parts, comprising a preparatorily-

set, potentially-movable locking-member equipped with a series of catches adapted to engage said first-named catches, and a key-controlled rotatable and depressible plunger adapted to free said locking-member to permit retraction thereof. 70

5. The combination with the sections of a case, of a series of catches carried by one of said sections, and co-acting mechanism carried by the other of said sections, comprising 75 a spring-retracted locking-member equipped with a series of catches adapted to automatically engage said first-named catches, means for latching said locking-member in "set" position against the force of its retracting 80 spring, and key-controlled means for releasing said locking-member from its latched condition to permit retraction of the locking-member.

6. The combination with the sections of a case, of a series of catches carried by one of said sections, and co-acting mechanism carried by the other of said sections, comprising a preparatorily-set longitudinally-shiftable locking-member provided with a series 90 of resiliently-carried hook-form catches adapted to engage said first-named catches automatically when the case-sections are closed, and means for retracting said locking-member. 95

7. The combination with the sections of a case, of a series of catches carried by one of said sections, and co-acting mechanism comprising a longitudinally-shiftable locking-member having one edge equipped with a series 100 of resiliently-carried hook-form catches adapted to engage said first-named catches, a spring adapted to retract said locking-member, a spring-catch carried by said locking-member and serving to engage a stationary catch when the locking-member is in the "set" position, a key-controlled revolvable and depressible plunger adapted to disengage said last-named catch, said plunger having a longitudinal slot and a circumferential recess, and a tumbler having a tooth adapted to engage said longitudinal slot and having also a tooth adapted to engage said circumferential recess. 110

8. The combination with a pair of case-sections provided with top flanges, of a series of depending studs carried by one of said flanges, and co-acting mechanism carried by the other of said flanges, comprising a spring-retracted locking-member slidably 120 suspended beneath said last-named flange and equipped with downwardly-bent hook-form catches adapted to automatically engage said studs when the case-sections are closed, means for releasably securing said 125 locking-member in the set position, and key-controlled means for releasing said locking-member.

9. The combination with a pair of case-sections having top flanges, of a series of de- 130

- pending studs carried by one of said flanges, and co-acting mechanism carried by the other of said flanges, comprising a spring-retracted slide equipped with a depending finger-piece and equipped also with catches adapted to engage said first-named catches, releasable means for holding said slide in "set" position, and key-controlled releasing means.
- 10 10. The combination with case-sections provided with top flanges, of a series of catches carried by one of said flanges, a sliding locking-member supported beneath the other of said flanges and equipped with a series of catches adapted to engage said first-named catches, and key-controlled means extending through said last-named flange

and adapted to control the movement of said sliding locking-member.

11. In locking means of the character set 20 forth, the combination of a spring-retracted slide equipped with a series of resiliently-carried hook-form catches projecting from one edge thereof and adapted to spring into automatic engagement with co-acting catches 25 when the sections of the case are closed, a catch adapted to maintain said slide releasably in "set" position, and a key-controlled device for releasing said last-named catch.

JOHN T. BINKLEY.
